DESIGN FOR A COAT

Morris Weinstein, New York, N. Y.

Application July 26, 1940, Serial No. 93,940

Term of patent 3½ years

To all whom it may concern:

Be it known that I, Morris Weinstein, a citizen of the United States and residing in Manhattan, in the city, county, and State of New York, have invented a new, original, and ornamental Design for a Coat, of which the following is a specification, reference being had to the accompanying drawing, forming part thereof, wherein:

Fig. 1 is a front view of a coat showing my new design.

Fig. 2 is a rear view thereof.

I claim:

The ornamental design for a coat, substantially as shown.

MORRIS WEINSTEIN.
